UNITED STATES PATENT OFFICE.

SAMUEL P. ALPAUGH, OF MARTINS FERRY, OHIO, ASSIGNOR TO WHEELING SANITARY MANUFACTURING COMPANY, OF WHEELING, WEST VIRGINIA.

DESIGN FOR A LAVATORY.

45,284.

Specification for Design.

Patented Feb. 24, 1914.

Application filed August 4, 1913. Serial No. 782,958. Term of patent 7 years.

To all whom it may concern:

Be it known that I, SAMUEL P. ALPAUGH, a citizen of the United States, residing at Martins Ferry, in the county of Belmont and State of Ohio, have invented a new, original, and ornamental Design for a Lavatory, of which the following is a specification, reference being had to the accompanying drawing, forming part thereof.

Figure 1 is a view in perspective; and

Fig. 2 is a rear elevation, showing my new design. Fig. 3 is a side elevation of the same.

I claim:

The ornamental design for a lavatory, as shown.

SAM. P. ALPAUGH.

Witnesses:

EDWARD J. LALLY,
S. R. JAQUAY.
